ASSIGNORS, BY MESNE ASSIGNMENTS, TO GOULD CAR LIGHTING CORPORATION, OF
ROCHESTER, NEW YORK, A CORPORATION OF MARYLAND.

EXHAUST MUFFLER.

Application filed February 16, 1922. Serial No. 536,900.

The invention relates to improvements in exhaust mufflers which are particularly adapted for use in connection with steam turbines, or the like. In steam turbines the steam leaves the turbine buckets in a succession of puffs succeeding one another at the frequency at which the buckets pass a given point. This frequency may be within the range of audible frequencies and in consequence an objectionable shrill noise may be caused which issues largely from the exhaust pipe.

bucket wheel 1 is mounted on the over-hang- 50
ing end of a shaft 2 which is illustrated as supported within a ball bearing 3 within a housing member 4 attached to a machine which may be driven by the turbine, a portion of which is indicated at 5 and which 55 may be an electric generator or other device. A casting 6 attached to the housing plate 4 is so formed as to serve as an enclosing member for the oil chamber 6¹ surrounding bearing 3, casting 6 also serving as a casting 60 member for the turbine bucket wheel 1.

The present invention is designed to provide an improved form of exhaust muffler 15 which may be used in connection with a device from which steam or other gas would otherwise issue at such frequencies as to produce audible sounds, the muffler operating in such a manner as to cause the exhaust to issue 20 therefrom practically without sound. This may be accomplished in accordance with the preferred form of the invention by the provision of means whereby the issuing steam or the gas is caused to travel through a plurality of circuitous paths of different lengths, 25 on their way to the exit opening of the muffler.

Another object of the invention is the provision of an improved turbine structure in 30 which an exhaust muffler is incorporated in the casing or in the cover plate of the turbine. Other objects and advantages of the invention will appear more fully hereinafter in the following specification.

In order that a clearer understanding of the invention may be had attention is hereby directed to the accompanying drawings forming part of this application and illustrating one embodiment thereof. In the 35 drawings

Fig. 1 represents a vertical section taken through a steam turbine of the general type described in Letters Patent No. 944,839, No. 1,042,871, and No. 1,254,465, and having a casing with an exhaust muffler secured thereto to constitute a covering means therefor, and Fig. 2 is a vertical section taken on line 2-2 of Fig. 1.

Referring to the drawings, the turbine

Attached to a flat face on the top of the casing member 6 is a nozzle and bucket guide member 7. Steam or other gas is supplied to the nozzle by a pipe 9 connected to the nozzle member 7 by the connection 8.

The outward end of the turbine case 6 is closed by a cover plate 10 secured to casing member 6 by suitable means such as the cap screws 11. A muffler cap 12 is secured by 70 suitable means such as the cap screws 13 to the cover plate 10.

Members 10 and 12 together form a muffler casing which is preferably of annular box like form as shown. The exhaust from the 75 turbine issues past the end of shaft 2 into a space 14 which preferably surrounds the axis of the muffler casing and is in alignment with shaft 2, from which space the exhaust steam or other gas passes to the exhaust 80 opening 15 of the muffler.

The muffler is so constructed as to provide a plurality of ribs about which the exhaust will have to pass on its way to the outlet 15. Preferably these ribs, 16, 17 and 85 18 are formed partly on cover plate 10 and partly on cap member 12. As is shown in Fig. 1 members 10 and 12, each have a portion of the ribs referred to directed towards the other, the aligned portions of these ribs 90 engaging along the plane indicated at 19, the adjacent faces of the contacting members being finished flat to provide an easily manufactured joint.

The annular rib 16 thus formed extends 95 across the muffler casing from one side to the other, surrounding space 14 into which the exhaust steam from the turbine wheel enters.

Rib 16 is provided with a plurality of separated openings 20 therethrough through which the steam will pass into the passage 21 surrounding rib 16. Annular rib 17 surrounds space 21 and is provided with a plurality of openings 22 therethrough which are in staggered relation with openings 20. Steam passes from the annular passage 21 through openings 22 into the annular passage 23 which extends between ribs 17 and 18. The steam passes from the annular passage 23 through openings 24 in rib 18 into the annular space 25, openings 24 being out of alignment with openings 22 in rib 17. The annular space 25, which is surrounded by casing member 12 leads the steam into the exhaust opening 15, which is shown as threaded to receive an exhaust pipe.

It will be noted that the turbine case with the cover plate and muffler cap completely enclose the turbine wheel. The space enclosed within the turbine case and cover plate communicates with the atmosphere only by the indirect paths leading from space 14 to exhaust opening 15, indicated by the arrows in the drawings. These paths also constitute the only channels through which sound waves may travel from the interior of the turbine casing to the discharge end of the exhaust pipe.

It will be observed that the paths through which the gases pass to the discharge opening are repeatedly reversed in direction. It will also be noted that a plurality of paths are provided between the entrance and exhaust openings of the muffler which are of different lengths each from the other. Thus some of the exhaust will proceed upwardly through the openings in ribs 16, 17 and 18 by a comparatively short path while another portion of the exhaust will pass through the lowermost opening in rib 16 and will have a longer path to travel to the discharge opening 15. In the passage from each annular space to the next annular space the exhaust will divide and pass through different openings so that at each reversal of direction of the exhaust steam or other gas the latter will divide between paths of different lengths. Accordingly the wave impulses passing through the muffler will be out of step with each other as they enter the exhaust opening 15 and will interfere so as to prevent the exhaust from leaving the opening 15 in a manner to set up sound waves in the outside atmosphere.

In the preferred form of device, as illustrated, a plurality of annular passages surrounding each other are provided, in each of which a portion of the sound propagating impulses are eliminated so that the impulses which would propagate sound are successively diminished from one stage to the other in what may be a geometric progression with the final result of nearly silent

running so far as concerns the noise which would otherwise be produced as the steam leaves the turbine buckets.

It may also be noted that sound suffers diminution when its course of travel is obstructed and that our construction provides an enclosure in which the sound waves are caused to pass through labyrinth-like passages in which the direction of travel is repeatedly reversed.

It should be noted that the invention is not limited strictly to the details of construction described but is as broad as is indicated by the accompanying claims.

What we claim is:—

1. In an apparatus of the class described the combination of a turbine having a casing surrounding the turbine wheel thereof, and an exhaust muffler rigid with the casing and forming an extension of the casing, part of the turbine wheel casing forming part of the muffler, and said muffler having baffling means rigid with said casing causing the exhaust gases to pass in a general radial direction through the muffler.

2. In an apparatus of the class described the combination of a turbine wheel, a casing member, a cover plate therefor and muffler cap member all rigidly secured with respect to one another and with the first two members substantially enclosing the turbine wheel, and muffling means carried rigid with and between the last two mentioned members.

3. Apparatus of the class described comprising a turbine and its casing having an exhaust outlet substantially at the turbine axis and a muffler rigidly secured with respect to the turbine casing and having its inlet connected with said exhaust outlet and also substantially at the turbine axis.

4. In an apparatus of the class described the combination of a turbine, said turbine having a casing providing a relatively flat thin chamber for the turbine wheel, and a relatively flat thin muffling chamber situated adjacent thereto and rigid therewith, the general plane of said chambers being substantially parallel and said chambers being connected for the passage of exhaust steam from one to the other substantially at the turbine axis.

5. In an apparatus of the class described, the combination of a turbine having a stationary casing for the turbine wheel, a cover plate member rigidly but removably secured to the casing, and a stationary muffler associated with the casing to form a unitary structure, said cover member also forming a wall of the muffler with integral muffler baffle plates thereon.

6. In an apparatus of the class described, the combination of a casing, a turbine wheel mounted therein upon a shaft, and a relatively flat muffling chamber spaced from

said wheel and lying in a general plane substantially parallel therewith, said muffling chamber being provided with a central intake opening also providing clearance for 5 said shaft.

7. In an apparatus of the class described, the combination of a casing, a turbine wheel mounted therein upon a shaft, and a relatively flat muffling chamber having a side 10 wall conforming substantially to the con-

tour of the face of said wheel but spaced therefrom and forming a cover plate for the turbine casing, said wall being formed with a central intake opening also providing clearance for said shaft. 15

Signed at Depew, in the county of Erie, and State of New York, this 14th day of Feb. A. D. 1922.
